UNITED STATES PATENT OFFICE.

BRAINARD TAYLOR BRUCE, OF PROVIDENCE, RHODE ISLAND, ASSIGNOR
TO UNDERWOOD TYPEWRITER COMPANY, OF NEW YORK, N. Y., A
CORPORATION OF NEW JERSEY.

TYPE-WRITER CARRIAGE.

SPECIFICATION forming part of Letters Patent No. 779,408, dated January 10, 1905.

Application filed February 23, 1904. Serial No. 194,669.

REISSUED

To all whom it may concern:

Be it known that I, BRAINARD TAYLOR BRUCE, a citizen of the United States, and a resident of Providence, Providence county, 5 Rhode Island, have invented certain new and useful Improvements in Type-Writer Carriages, of which the following is a specification.

My invention relates to carriages for type-writers and like machines, and has for its object to provide improved means for holding and feeding a plurality of writing-surfaces for the purpose, as an instance, of enabling a series of originals to be produced successively 10 on separate sheets of paper while duplicates thereof are made at the same time on a continuous sheet or strip.

The invention will be fully described hereinafter and the features of novelty pointed 15 out in the appended claims.

Reference is to be had to the accompanying drawings, in which—

Figure 1 is a top view, with parts broken away, of so much of a type-writer carriage as 20 is required to illustrate my invention. Figs. 2 and 3 are sectional elevations on lines 2 2 and 3 3, respectively, of Fig. 1; and Fig. 4 is a rear view of the rear paper-shelf.

A designates the frame carrying the platen 25 30 B. These parts may be constructed in any approved manner, as may also the feed-rollers C, which coöperate with the platen B to bring the paper forward.

In the rear of the platen (in case of a front- 35 strike machine) are located two paper-shelves E E', converging toward the platen and terminating about tangentially thereto. One of these shelves, or both, may be provided 40 with guide-fingers conforming to the curvature of the platen and lying close thereto. In the construction illustrated the fingers E' of the front shelf E are located at the ends and the fingers E' of the rear shelf at the center, with sufficient space between adjacent fingers to accommodate the feed-rollers C. Other 45 means, however, may be provided for properly guiding the paper around the platen B.

For feeding the paper or writing surface

which passes between the shelves E E', I provide a separate feed device, (independent of the rollers C.) This auxiliary device, as shown, 50 may consist of a series of rubber rollers F', secured to or journaled upon an axle or shaft F, which is carried by brackets E' on the rear shelf E'. These rollers F' are located mainly 55 in the rear of said shelf, but project through openings E' therein, so that the said rollers are about flush with the supporting-surface of the shelf E' or slightly in advance thereof. Between the two shelves and immediately adjacent to the rollers F' is located another set of rollers, F', secured upon a shaft F', which is journaled in stationary plates or brackets G. The front shelf E may also be secured to these brackets, preferably in such a manner as to 60 be removable readily. A handle or knob F' is provided at the end of the shaft F' to enable it to be turned.

In the use of my invention a long strip of paper with a strip of copying-paper under it 70 is fed between the platen B and the front shelf E. A sheet of letter-paper or the like is then inserted between the rollers F' and F', and by turning the handle F' the sheet of paper is fed downward until it is within the reach of the 75 platen B and the ordinary feed-rollers C. By then turning the platen both the sheet of paper and the strip will be fed simultaneously to the printing position. After the sheet of paper has been written upon and removed 80 from the machine the next sheet is inserted and fed to the proper position by the rollers F' and F', while the strip remains stationary until the platen is turned to feed both the sheet and the strip. Thus there will be pre- 85 served on the strip a continuous record or copy of all matters written upon the separate sheets of paper. If desired, the front shelf E may be removed and then the machine can be used in the customary manner with or 90 without the auxiliary feed-rollers F' F'. The provision of the feed-rollers C is not absolutely essential. I have illustrated them because this is the usual construction.

Various modifications may be made without 95 departing from the nature of my invention.

I claim as my invention and desire to secure by Letters Patent—

1. In a type-writer or like machine, a platen and a plurality of paper-shelves located adjacent thereto and provided with fingers conforming to the curvature of the platen, the fingers of all of the shelves lying in the same cylindrical surface.
2. In a type-writer or like machine, a platen and a plurality of paper-shelves located adjacent thereto and each provided with fingers extended partly around the platen at different points thereof, the fingers of all of the shelves lying in the same cylindrical surface.
3. In a type-writer or like machine; a platen, a plurality of paper-shelves leading thereto, and a paper-feed device located between said shelves.

4. In a type-writer or like machine, a platen, a plurality of paper-shelves leading thereto, and a paper-feed device, independent of the platen, for feeding the paper between said shelves.

5. In a type-writer or like machine, a platen, a plurality of paper-shelves leading thereto, a set of feed-rollers projecting through one of said shelves, and another set of feed-rollers arranged between the shelves and coöperating with the first-named set of rollers.

In testimony whereof I have hereunto set my hand in the presence of two subscribing witnesses.

BRAINARD TAYLOR BRUCE.
